UNITED STATES PATENT OFFICE

LUCIEN NICOLAS HENRY, OF SOISSONS, FRANCE

APPARATUS FOR FLESHING HIDES, SKINS OR THE LIKE

Application filed December 28, 1927, Serial No. 243,195, and in France February 14, 1927.

My invention relates to an apparatus for use for fleshing or scraping hides, which by reason of its simple and easy manipulation avoids the necessity of employing skilled 5 labour.

The apparatus is characterized essentially by the employment of a circular rotary cutting blade, which is adapted to be so regulated as to allow strips of flesh varying in 10 thickness to be removed, according to the part of the hide which is being treated.

The apparatus is moreover so constructed that it is adapted to be displaced on the skin or hide in any required direction and adapted 15 to be regulated or adjusted without the workman having to remove his hands from the framework of the machine upon which they are resting.

With these objects in view, the axle of the 20 rotary cutter is operated from a flexible shaft connected to an electric motor suspended from a runway and displaceable within the workshop. This axle is mounted in a frame adapted to oscillate in a vertical plane, the 25 oscillations of the frame being controlled from those of two cams operated by the fingers of the workman whose hands are applied to the neighbouring handles, permitting of the displacement of the socket.

30 This tool holder may also be adjusted longitudinally in such a manner as to allow of regulating the distance between the active part of the cutting blade and the front part of the frame which presses down upon the 35 hide to be fleshed.

Moreover the apparatus may be provided with a sort of shield suitably shaped to reject or throw off on all sides the strips of cut flesh.

40 In order that my invention may be better understood it will now be described with reference to the accompanying drawings which shows by way of example a simple mode of construction and an improved embodiment 45 of a machine for fleshing hides or skins made according to my invention.

Figs. 1, 2, 3 and 4 show the first mode of execution.

50 Fig. 1 is a side elevation partly in section. Fig. 2 is a front elevation.

Fig. 3 is a part plan on a level with the line A—A, Fig. 1.

Fig. 4 shows to a smaller scale the arrangement of the unit constituting the apparatus and its driving mechanism. 55

Fig. 5 is a front elevation partly in section of a second mode of execution.

Fig. 6 is a plan view partly in section.

As will be seen from the drawings, according to the first mode of construction, the machine is provided with a socket or base 1 having a shoe 2 at the front intended to remove or smooth out creases in the hide or skin whilst being pushed forward during the work. The movement forward is facilitated 60 by a slightly oblique lower surface 2¹ provided at the lower portion of the shoe. 65

The base or socket is fixed to a frame 3, between the uprights or standards of which is disposed at the rear a spindle 4 upon 70 which are pivotally mounted lugs or extensions 5 made integral with the tool holder 6 which is, for example, cylindrical.

In the tool holder is mounted, preferably 75 on ball bearings, a rotary spindle 7, to the end of which is attached by means of a plate 8, a circular blade 9, preferably with a lower bevelled edge 9¹ and brought substantially into the horizontal position by a suitable inclination given to the tool holder. 80

Underneath this latter is fixed a sort of shield 10 with an incurved lateral surface and extending as far as 10¹ and opening out on either side of the spindle, in such a manner that the strips of cut flesh are ejected or 85 thrown away from the apparatus.

The tool holder 6 is provided with two lateral handles 11 and carries two pivotal axles 12 for cams 13 which are under the control of springs 14 attached to the tool holder on the one hand and on the other hand rest on a wedge 15 displaceable in the frame in such a manner as to regulate or adjust the initial inclination of the system when at rest, an inclination which as has already been seen, in which the bevel of the blade is substantially horizontal, with the plane of the upper portion of the blade directed under the rear edge 95 of the shoe 2.

The cams 13 are provided with hook pieces 100

16, into which the workman hooks his forefinger, which allows him, whilst still holding the handles 11, to oscillate the cams from the position 13 to another position 13^a, thus 5 determining the various inclinations for the blade between the positions 9 and 9^a, and thus allowing, during working, the thickness of the layer of flesh being removed to be varied according to the region of the hide 10 which is being treated, the back, head, feet, udder or the like.

As regards the initial regulation by means of the wedges 15 this is effected according to the type of work to be done and the nature 15 of the hide to be treated.

The rotary spindle of the machine is coupled by a flexible shaft 17 to a small electric motor 18 (Fig. 4) provided with a reverser, which imparts to it a movement of rotation 20 of suitable speed. This motor may be suspended on a loop 19 hooked to a groove pulley 20 running on a suitable rail, cable or profile track. This arrangement allows the motor to follow the movements of the apparatus in 25 a longitudinal direction, without interfering with the pliability of the flexible shaft coupling.

The skin or hide to be treated is stretched out and maintained on a horizontal table 22, 30 covered with a sheet of zinc 23. The workman takes hold of the apparatus by the handles and pushes it in a forward direction over the skin. The apparatus works like a plane and carries away shreds or strips of 35 flesh adhering to the skin.

The workman then brings the apparatus again to the rear and again pushes it forward to remove a fresh strip of flesh and so on, over the whole surface. When he comes to a part 40 which is more fleshy, as for instance the head, the feet or the udder, he operates upon the cams with the forefinger in such a way as to remove a much greater thickness of flesh.

The unit mechanism may with advantage 45 be completed or associated with means for sharpening the cutting blade during the displacement or when changing the hide. For this purpose one or two grindstones 24 may be provided, say one hard and one soft, 50 which are sprayed with water and which extend to the level of the work bench, so that it is only necessary to push the apparatus over these stones to obtain the required sharpening, the blade and the stone turning together.

55 In the second mode of execution shown in Fig. 5, the circular cutting blade 9 is bevelled at its upper edge. The direction in which it works being determined by the bisector of the angle of the bevel which must form an angle 60 of about 10° with the surface of the hide, this arrangement allowing a very wide cut with the least possible inclination.

The socket or base 2 is provided at 25 between the standards with a wide hollow to 35 prevent the heaping up of flesh between the

shield 10 and the base, it is also provided at 26 (Fig. 6) with a discharge opening. The strips of flesh will thus be easily evacuated and will not impede the movement of the tool holder. The latter having for example the 70 shape of a prism of square section is provided at its lower part with a cylindrical portion. The axle 7 rotates in roller bearings 27 and its vertical position is set by means of two ball abutments 28. It may thus rotate at a 75 considerable speed.

The frame is provided with a horizontal slot 30 in which the pivotal axle 4 of the tool holder accomplishes a sliding motion under the action of a milled nut 31 which moves 80 the screw 32 and the bushing 29 through which said pivotal axis passes.

This arrangement allows of regulating the distance between the active part of the cutting blade and the lower back angle of shoe 2. 85 Said distance decreasing when the blade is being sharpened it will be necessary to push the latter forward.

The sliding movement of the wedges 15 which in combination with the cams 13 determine the vertical position is easily controlled by screws 33 moved by means of milled nuts 34. The tool holder is provided on the other hand with screwthreaded dowel pins 35 which allow the transverse locking of the 95 wedges by means of the milled nuts 36. Standard gradations are engraved upon the frame for the guiding of the regulator thus allowing of regulating with accuracy the cutting depth of the blade for the initial position of the cams determined as before by the action of springs 14. The tension of the latter may be regulated by a screw and nut device, it must be sufficient to lift back the tool holder in the top position of the apparatus 100 when at rest.

The axis of rotation of the cutting blade is advantageously connected to the flexible shaft by means of a cone 37 engaging in the corresponding part of the flexible shaft. 110 The screwing down of the screw threaded bearing 38 ensures the strength of the joint and allows of taking the apparatus to pieces without any difficulty.

The table of the apparatus may be mounted advantageously upon screwjacks in order to allow of varying its height according to the size of the workman and the hide is suitably stretched on the table by lateral windlasses by the intermediary of hooks. 120

The apparatus thus described may be applied to all kinds of work in tanning and currying, where it is required to remove a thin layer or shaving from the leather as for 125 fleshing in running water, paring in running water, fleshing during tanning, paring during tanning, smoothing during tanning and so on.

I declare that what I claim and desire to 130

secure by Letters Patent of the United States
is:—

1. In an apparatus for fleshing hides, skins and the like, a circular cutting blade, a rotary axle for said blade, a tool holder carrying the axle, a frame, a pivot for the tool holder upon said frame, wedges provided with an inclined bearing surface secured upon the frame, means for controlling the position of said wedges upon the frame, cams bearing upon the wedges, pivotal axes for said cams upon the tool holder, a resilient connection between the latter and said cams and means for controlling the rotation of said cams and causing the inclination of the tool holder to vary.
  2. In an apparatus for fleshing hides, skins and the like, a circular cutting blade, a rotary axle for same, a tool holder carrying said axle, a frame, a pivotal axle for the tool holder and means to control its displacement on the frame, adjustable wedges provided with upper inclined surfaces, two cams bearing upon said wedges, pivots for said cams, carried upon the tool holder, a resilient connection between the tool holder and said cams, an operating finger on both cams and a handle on said tool holder to allow of moving the apparatus and to modify at will the cutting depth of the blade.
  3. In an implement for fleshing hides, a base having a projecting hide smoothing shoe, means to manually move the base over the surface of a hide, a pivoted knife mounted on the base, means to manually alter the inclination of the knife during the manual movement of the base over a hide, and means to rotate the knife.
  4. In an implement for fleshing hides, a base having a projecting hide smoothing shoe having a slightly bevelled under surface, a pivoted knife, means to adjust the normal inclination of the knife, and manual means to additionally adjust the inclination of the knife during the movement of the implement over a hide.
  5. In an implement for fleshing hides, a base having an opening therethrough, means to manually move the base over a hide, a knife mounted in said opening, means to pivot the knife to incline it to a hide surface, and manual means to vary the inclination of the knife during the movement of the implement over a hide.
- 55 In testimony that I claim the foregoing as my invention I have signed my name.

LUCIEN NICOLAS HENRY.
